WITNESS:

Archer H. Harris

INVENTOR.

BY *Victor J. Evans*

ATTORNEY

UNITED STATES PATENT OFFICE.

ARCHER H. HARRIS, OF CHATTANOOGA, TENNESSEE.

DESIGN FOR AN AUTOMOBILE TIRE.

Application filed April 18, 1922. Serial No. 1,820. Term of patent 14 years.

To all whom it may concern:

Be it known that I, ARCHER H. HARRIS, a citizen of the United States of America, residing at Chattanooga, in the county of Hamilton and State of Tennessee, have invented a new, original, and ornamental Design for Automobile Tires, of which the following is a specification, reference being had to the accompanying drawings, forming a part hereof.

Figure 1 is a plan view showing my new,

original and ornamental design for automobile tires, and

Figure 2 is a transverse sectional view.

I claim:

The ornamental design for an automobile tire as shown.

ARCHER H. HARRIS.

In the presence of—

L. H. LIGHTFOOT,
BEN L. TAYLOR.
